LIQUEFIER BOWL COVER

William B. Kochner, St. Louis, Mo., assignor to
Knapp-Monarch Company, St. Louis, Mo., a
corporation of Delaware

Application August 25, 1952, Serial No. 21,179

Term of patent 14 years

(Cl. D89—1)

To all whom it may concern:

Be it known that I, William B. Kochner, a citizen of the United States and a resident of the city of St. Louis, State of Missouri, have invented a new, original, and ornamental Design for a Liquefier Bowl Cover, of which the following is a specification, reference being had to the accompanying drawing, forming a part thereof, in which:

Figure 1 is a top plan view of a liquefier bowl cover, showing my new design.

Figure 2 is a side elevational view thereof.

Figure 3 is an enlarged sectional view on the line 3—3 of Figure 1; and

Figure 4 is an enlarged perspective view of the portion of the cover shown in Figure 3.

I claim:

The ornamental design for a liquefier bowl cover, substantially as shown.

WILLIAM B. KOCHNER.
